BY MESNE ASSIGNMENTS, TO TAYLOR LABORATORIES INC., OF NEW YORK, N. Y., A
CORPORATION OF NEW YORK.

CONVERSION OF CELLULAR OR FIBROUS MATERIAL.

Application filed July 29, 1919. Serial No. 314,102.

This invention pertains to the conversion of a substance from one physical state to another. The invention pertains more particularly to the conversion of organic material from what might be termed, the cellular or fibrous condition to that condition or state in which substantially no semblance of organized structure may be discerned, and especially to the conversion of cellulose such as cotton to a material or substance which might be described as having substantially the characteristics of a solid. At present various means are being employed for accomplishing this purpose, for instance, fibrous or cellular material, such as cotton, may be dissolved in a cupro ammonium solution such as Schweitzer's reagent, precipitating the cellulose from this solution by adding an acid and diluting with water, washing the gelatinous material, so obtained to free it from all traces of metallic compound, consolidating the mass so obtained by pressure and molding and drying the material for various commercial uses. Processes of this order are necessarily slow and expensive, the amount of solution constituents lost in the washing is large and recovery is impossible or impracticable owing to the dilution.

The main object of the present invention is to largely, if not entirely, overcome these difficulties.

Further objects as well as the advantages obtaining will be apparent to those versed in these matters upon reading the following specification in which one method of carrying our inventive idea into effect is described.

Obviously any suitable apparatus may be employed in practising the invention and any suitable means may be resorted to for accomplishing the several steps of the process. One convenient and preferred method of operating may be described as follows:

Hydrated cupric oxide is added to concentrated ammonia until it ceases to dissolve. Cotton or similar cellular material is added to this solution to a point of saturation, resulting in a various mass. This mass is then placed in a closed electrolyte cell containing suitable electrodes and subjected to the action of an electric direct cur-

rent. Cellulose, which we believe to be in the form of hydrate, begins to separate at once, being deposited on the positive electrode (anode) in substantially colorless films, flakes or layers of almost rubber-like consistency depending on the current density, while simultaneously copper is deposited on the negative or cathode. The current may be passed at a high electrode density heating the bath to the boiling point and driving off the ammonia, which is recovered in suitable condensing arrangements, or another source of heat may be employed to drive off the ammonia. Both copper and ammonia so obtained are immediately available for conversion into fresh solution, or other use.

The solutions of cellulose preferably should be handled at all times in a highly concentrated state. This permits of a maximum output from a minimum sized plant. The electrolytic treatment removes all or substantially all of the solvent reagent, thus leaving the cellulose in especially pure form and advantageous condition for use or further treatment. The solvent chemicals, copper and ammonia, are economically recovered and may be used to dissolve further cellulose, etc., for treatment.

The gelatinous deposit of cellulose so obtained is practically chemically pure and requires no further washing or purification for many purposes. The product is non-cellular and non-fibrous in form and is readily resoluble in cupro-ammonia or the original solvent used, whereas the products obtained by prior processes are scarcely resoluble in such solvents. Our product is more soluble in cupro-ammonia than the original fibrous or cellular cellulose. We also find that the product substantially retains its original capability of being nitrated to form pyroxylene, etc. Our product will withstand boiling in water for exceptionally long periods.

The cellulose while in this condition is somewhat soluble in certain volatile solvents and may be used for the manufacture of varnishes, films or plates, threads, etc., of an exceedingly tough and flexible nature.

The cellulose may also be partly dehydrated by heat and, with or without admix-

ture of other materials, compacted by pressure and heating into sheets, blocks and moulded articles in general.

The material so obtained is highly resistant to all chemical reagents, is exceedingly strong, resists weather and decay indefinitely and is also resistant to high temperature.

In the accompanying drawing we have 10 illustrated in vertical cross-section, a suitable form of electrolytic bath adapted for practicing the invention.

1 indicates the tank, 2 the cover therefor, 3—3' the copper cathodes, and 4 the platinum anode electrically connected as shown. 15 5 indicates the electrolyte, and 6 a suitable outlet for the ammonia vapors. The cellular or colloidal material is collected upon the platinum electrode and the metallic copper therefrom is collected upon the copper electrodes from which it may be recovered 20 from time to time as the process is pursued.

The anode and cathode are preferably spaced about 6 inches apart and good results have been obtained using a current density of two-tenths of an ampere per 25 square inch of anode surface.

Having described one method of practicing the inventive idea it is to be understood that altho specific terms have been employed they have been used in the descriptive and generic sense and not for purposes of limitation, the scope of the invention being set forth in the claims.

35 We claim:—

1. The method of converting an organic substance from a cellular state to a more dense material which consists in dissolving said substance in a suitable solvent and removing said substance from said solvent electrolytically.

2. The method of converting an organic substance from a cellular state to a more dense material which consists in dissolving 45 said substance in a suitable electrolyte, and then energizing said electrolyte to release said substance in a converted state and depositing it electrolytically on an anode.

3. The method of converting an organic 50 substance from a cellular state to a more dense material which consists in dissolving said substance in a suitable solvent and removing said substance from said solvent electrolytically, and also recovering the solvent constituents.

4. The method of converting an organic substance from a cellular state to a more dense material which consists in dissolving 55 said substance in a suitable solvent and collecting said substance from said solvent upon an electrode.

5. The process which consists in dissolving 60 cellulosic material and subjecting the solution to electrolysis.

6. The process which consists in dissolv-

ing cellulosic material in a solvent thereof, and passing an electric current through the solution from an anode to a cathode whereby the cellulose is deposited on the anode.

7. The process which consists in dissolving 70 cellulosic material in a metal salt solvent, and subjecting the solution to electrolysis between an anode and cathode, whereby cellulose is deposited on the anode and the metal of the salt is deposited on the 75 cathode.

8. The process which consists in dissolving 80 cellulosic material in fibrous condition in a solvent thereof, and electrolyzing the solution between an anode and cathode, to deposit the cellulose on the anode.

9. The process which consists in dissolving 85 cellulosic material in cupro-ammonia solution, and electrolyzing the solution between an anode and cathode, to deposit the cellulose on the anode and the copper on the cathode.

10. The process which consists in dissolving 90 cellulosic material in fibrous condition in a solvent thereof, and electrolyzing the solution between an anode and cathode, to deposit the cellulose on the anode, and recovering the solvent constituents for reuse.

11. The process which consists in dissolving 95 cellulosic material in a solvent thereof, and passing an electric current through the solution from an anode to a cathode whereby the cellulose is deposited on the anode, and recovering the solvent constituents for reuse.

12. The process which consists in dissolving 100 cellulosic material in cupro-ammonia solution, and electrolyzing the solution between an anode and cathode, to deposit the cellulose on the anode and the copper on the cathode, and recovering the deposited copper and the ammonia from the solution for reuse.

13. The method of producing cellulose 110 consisting in passing an electric current through electrodes in contact with a cellulose electrolyte.

14. The method of removing solvent constituents from a solution of cellulose which consists in passing an electric current 116 through the dissolved cellulose to remove solvent material therefrom electrolytically.

15. The method of treating cellulosic material which consists in dissolving the material in a solvent of cellulose and passing 120 an electric current through the dissolved cellulose to remove solvent constituents therefrom by the aid of electrolytic action.

16. The process of treating cellulosic material which consists in dissolving the material in solvent therefor containing a metal and subjecting the cellulose solution to electrolysis to remove the solvent metal from the cellulose electrolytically.

17. The new article of manufacture comprising substantially pure cellulose having 130

the characteristics that it is non-cellular and non-fibrous in form, is readily soluble in cupro-ammonia solution and is capable of being nitrated substantially as ordinary cellulose.

18. The new article of manufacture comprising a cellulose body having the characteristics that it is non-cellular and non-fibrous in form, and is readily soluble in cupro-ammonia solution.

19. The new article of manufacture comprising a cellulose body having the characteristics that it is non-cellular and non-fibrous in form, and is readily soluble in cupro-ammonia solution and is capable of being nitrated substantially as ordinary cellulose.

20. The new article of manufacture comprising cellulose deposited electrolytically from a solution of cellulose and having the characteristics that it is non-cellular and non-fibrous in form, and is readily soluble in cupro-ammonia solution.

21. The new article of manufacture comprising cellulose deposited electrolytically

from a solution of cellulose and having the characteristics that it is non-cellular and non-fibrous in form, and is readily soluble in cupro-ammonia solution and is capable of being nitrated substantially as ordinary cellulose.

22. The method of removing metallic constituents from organic material which consists in passing an electrolytic current therethrough to remove the metal by electrolytic action.

23. The method of removing metallic constituents from cellulosic material which consists in passing an electrolytic current through the cellulosic material in an electrolytic cell whereby the metal is removed from the cellulosic material by electrolytic action and electro-deposited on an electrode of the cell.

In testimony whereof we hereunto affix our signatures.
